UNITED STATES PATENT OFFICE.

IRA CROSS, OF NASHUA, NEW HAMPSHIRE.

LOOM-SHUTTLE.

SPECIFICATION forming part of Letters Patent No. 375,265, dated December 20, 1887.

Application filed August 22, 1887. Serial No. 247,553. (No model.)

To all whom it may concern:

Be it known that I, IRA CROSS, of Nashua, county of Hillsborough, and State of New Hampshire, have invented an Improvement 5 in Loom-Shuttles, of which the following description, in connection with the accompanying drawings, is a specification, like letters on the drawings representing like parts.

This invention has for its object to improve 10 that class of shuttles wherein the bobbin has an inside groove to be engaged by a shoulder on the spindle.

Prior to my invention a spindle having a shoulder to engage an inside groove has been 15 provided with a long heel, upon which has been riveted a flat spring to act against the periphery of the bobbin-head and press the bobbin upon the shoulder, and so, also, a spindle has been provided with a pin carrying a 20 presser to act on the periphery of the bobbin.

In my invention the long heel for the spindle and its attached spring are omitted, and instead I employ a stationary pin, which arrests the head of the bobbin just before the 25 spindle comes into central position in the shuttle-body, the arrest of the bobbin enabling the shoulder at the under side of the shuttle-spindle to enter the inside groove.

Figure 1, in longitudinal section, shows a 30 shuttle embodying my invention, the spindle and shuttle being in working position; and Fig. 2 is a like view, with the shuttle and bobbin, but partially shown, turned out of the shuttle-body.

The shuttle-body A is and may be of usual 35 construction.

The spindle B, pivoted on a pin, B', has at its under side a shoulder, b. The bobbin C has at the inner side of its base an inside 40 groove, c. The short bed b' of the head of the spindle is acted upon by a plunger, d, in turn acted upon by a spiral spring, d', the plunger acting to hold the spindle in the two positions

shown in the drawings. The shuttle-body is provided with a bobbin-arresting pin or projection, e. 45

In practice, the bobbin, of any usual shape, but having an inside groove, is placed upon the shouldered spindle B while the latter is turned out of the shuttle, as in Fig. 2, and 50 thereafter the spindle is turned into the shuttle-body, as in Fig. 1. In doing this the bobbin strikes against the arresting pin or projection e just before the spindle reaches its proper central position parallel to the center 55 line of the shuttle-body, and as a result thereof the head of the bobbin is arrested before the movement of the spindle is completed about its pivot B', and the collar or projection b is made to enter the inside groove of the bobbin. 60

The construction herein shown is simpler and cheaper than anything known to me capable of accomplishing a like purpose.

Prior to my invention I am aware that a 65 bobbin having an outside groove has been retained upon a spindle by means of a stationary pin which was embraced by the said groove when the bobbin and spindle were turned into the shuttle-body.

I claim—
70
The shuttle-body, the bobbin-receiving spindle having a shoulder, b, at its under side, combined with an arresting pin or projection, e, secured to the shuttle-body and acting to arrest the bobbin held upon the spindle just 75 in advance of the arrival of the said spindle in central position in the shuttle-body, substantially as described.

In testimony whereof I have signed my name to this specification in the presence of two sub- 80 scribing witnesses.

IRA CROSS.
